US00D457520S

(12) **United States Design Patent** (10) Patent No.: **US D457,520 S**
Laverick et al. (45) Date of Patent: **** May 21, 2002**

(54) **INPUT CONTROLS FOR A WIRELESS COMMUNICATIONS DEVICE**

(75) Inventors: **David Laverick**, Overland Park; **David Lammers-Meis**, Prairie Village; **Robert M. Kalis**, Overland Park, all of KS (US)

(73) Assignee: **Garmin Ltd. (KY)**

(**) Term: **14 Years**

(21) Appl. No.: **29/147,545**

(22) Filed: **Aug. 30, 2001**

(51) LOC (7) Cl. **14-03**

(52) U.S. Cl. **D14/247**

(57) **CLAIM**

The ornamental design for a input controls for a wireless communications device, as shown and described.

DESCRIPTION

FIG. 1 is a perspective view of a input controls for a wireless communications device of the present invention;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showings throughout the views are for illustrative purposes only and form no part of the claimed design.
